UNITED STATES PATENT OFFICE.

MAX MERTENS, OF BERLIN, GERMANY, ASSIGNOR TO GENERAL ELECTRIC COMPANY,
A CORPORATION OF NEW YORK.

ELECTRICAL-CURRENT-LIMITING DEVICE.

1,099,562.

Specification of Letters Patent.

Patented June 9, 1914.

Application filed November 14, 1911. Serial No. 660,272.

To all whom it may concern:

Be it known that I, MAX MERTENS, a subject of the Emperor of Germany, residing at Berlin, Germany, have invented certain new and useful Improvements in Electrical-Current-Limiting Devices, of which the following is a specification.

My invention relates to electrical current-limiting devices and has for its object the construction of an improved form of such apparatus.

Electrical current-limiting devices are frequently used with electrical circuits, usually of small capacity, feeding lamps or other translating devices, where it is desired to limit the consumption of current or energy taken by such circuits. These devices usually operate to intermittently break the circuit when the number of lamps or other 20 translating devices connected thereto consume more than a predetermined amount, or consist of devices where resistance is switched or connected in series with the circuit, so that the translating devices will not 25 operate satisfactorily. By such means the attention of the consumer is called to the fact that he is endeavoring to use more energy or current than that to which he is entitled.

30 My invention consists in a new form of current-limiting device and comprises a special form of mechanism whereby if the current in the circuit exceeds by a small amount a predetermined value the circuit 35 will be intermittently interrupted, but if this value is exceeded by a large amount the circuit will be permanently opened.

The further novelties of my invention are pointed out with more particularity in the 40 claims appended to and made a part of this specification.

For a further understanding of my invention, reference may be had to the accompanying drawing where 1 shows my device 45 connected to an electrical circuit supplying from a source 2 by means of conductors 3, 4, lamps or other translating devices 5.

6 and 7 are binding-posts which are connected in series with one of the conductors. 50 From binding-post 6 extends conductor 8 to one end of winding of solenoid 9; the other end being connected by conductor 10 to terminal 11, which is fastened to a metal plate 12. Upon this plate is a pin 13 about

which swings an L-shaped lever having two 55 arms 14, 15.

Passing through the solenoid is a core 16, the head 17 of which is adapted to strike arm 15 of the lever and move this in an upward direction. If this arm is moved upward more than a certain amount it will be caught by the spring latch 18 and held in the position shown by the dotted lines until released by pressure upon the button 19 which extends beyond the casing, not shown, 65 of the device. The length of stroke of core 16 is limited by stop 20 fastened to bar 21 having a slot 22 in operative relation with a screw 23, so that the position of this stop may be changed in the well known manner. 70

On arm 14 of the lever is a contact 24 which is arranged to make contact with contact 25 conductively fastened to binding-post 7.

The operation of my device will be as follows: When the consumer connects to the circuit a number of lamps or translating devices greater than a predetermined one, so that more than a given amount of current will be consumed, the current flowing in the 80 circuit, and hence through the solenoid, will be of such a value as to pull up core 16, causing it to strike against arm 15 of the lever and break the connection between contacts 24 and 25. As soon as this connection 85 is broken, the circuit of the solenoid is opened its core will drop and the contact will be remade, to be broken again in the manner described, so that the current is intermittently interrupted until the consumer 90 disconnects from the circuit the excess of translating devices connected thereto. If there are connected to the circuit a number of translating devices greatly in excess of the predetermined number, the instant- 95

neous flow of current in the circuit immediately after the connection of such devices will be of such strength that the core 16 will be more powerfully attracted than before, and by its greater upward movement 100 arm 15 of the lever will be so greatly deflected that its return to its normal position will be prevented by latch 18 and it will assume the position shown by the dotted lines. The current in the circuit will then be per- 105 manently interrupted and its flow only restored after the consumer has pressed button 19. By this action of intermittently in-

2
interrupting the current if the predetermined value is slightly exceeded, and by permanently interrupting the same if the value is greatly exceeded, the consumer's attention is 5 called to the approximate excess of lamps or other translating devices which he has connected to the circuit.

It will be obvious that my device may be used as shown, or, if desired, an electric 10 meter may also be connected to the circuit and such connection has not been illustrated.

While I have illustrated a preferred embodiment of my invention, I do not limit myself to this embodiment, but seek in the 15 appended claims to cover all embodiments which will be obvious to those skilled in the art and not depart from the spirit of my invention.

What I claim as new and desire to secure 20 by Letters Patent of the United States, is,—

1. A current-limiting device comprising means for intermittently interrupting the current when the current exceeds a predetermined value, and means for locking the 25 current interrupting means in open circuit position when the current exceeds a greater value.

2. A current-limiting device comprising means for intermittently interrupting the 30 current when the current exceeds a predetermined value, means for locking the current interrupting means in open circuit position when the current exceeds a greater value, and means for releasing the current 35 interrupting means when locked in open circuit position.

3. A current-limiting device comprising means for intermittently interrupting the current when the current exceeds a predetermined 40 value, means for locking the current interrupting means in open circuit position when the current exceeds a greater value, and manually operable means operatively related to said locking means for releasing the current interrupting means when 45 locked in open circuit position.

4. In combination, an electric circuit, a current-limiting device included therein and comprising means for intermittently interrupting 50 the flow of current in said circuit when the current exceeds a predetermined value, and means for holding the current interrupting means in open circuit position when the current exceeds a greater value.

5. In combination, an electric circuit, a current-limiting device included therein and comprising means for intermittently interrupting 55 the flow of current in said circuit when the current exceeds a predetermined value, means for holding the current interrupting means in open circuit position when the current exceeds a greater value.

60

interrupting means in open circuit position when the current exceeds a greater value, and means for releasing the current interrupting means when held in open circuit position.

6. In combination, an electric circuit, a 65 current limiting device included therein and comprising means for intermittently interrupting the flow of current in said circuit when the current exceeds a predetermined value, means for locking the current interrupting means in open circuit position when the current exceeds a greater value, and manually operable means operatively related to said locking means for releasing the current 70 interrupting means when locked in open circuit position.

7. In combination, an electric circuit, a current-limiting device comprising a coil included in said circuit, a circuit-breaking device in operative relation with said coil 80 for intermittently interrupting the flow of current in said circuit when the current exceeds a predetermined value, and latching means for holding the circuit-breaking device in open circuit position when the current 85 exceeds a greater value.

8. In combination, an electric circuit, a current-limiting device comprising a coil included in said circuit, a circuit-breaking device in operative relation with said coil for 90 intermittently interrupting the flow of current in said circuit when the current exceeds a predetermined value, latching means for holding the circuit-breaking device in open 95 circuit position when the current exceeds a greater value, and means for releasing said latching means.

9. In combination, an electric circuit including a circuit-breaking device, a current-limiting device comprising a solenoid included in said circuit, a core for said solenoid in operative relation with said circuit-breaking device and adapted to give a slight movement to the device when the current in said circuit exceeds a predetermined value 100 and to release the device when the circuit is broken so that the current in the circuit is intermittently interrupted and to give a greater movement to the device when the current is of greater value, latching means 105 for holding the circuit-breaking device in open circuit position when the current exceeds said greater value, and means for releasing said latching means.

In witness whereof, I have hereunto set 115 my hand this 9th day of October, 1911.

MAX MERTENS.
